UNITED STATES PATENT OFFICE

WILLIAM J. FIEGEL, OF DETROIT, MICHIGAN, ASSIGNOR TO BOHN ALUMINUM & BRASS CORPORATION, OF DETROIT, MICHIGAN, A CORPORATION OF MICHIGAN

CONTROL MEANS FOR MOLDING MACHINES

Original application filed October 11, 1926, Serial No. 140,948. Divided and this application filed September 17, 1928. Serial No. 306,574.

This invention relates to molding machines and more particularly to means for controlling the operation of the ram.

This application is a division of my co-pending application, Serial No. 140,948 filed Oct. 11, 1926.

One of the primary objects of the present invention is to provide means associated with the valve controlling the power to the ram capable of arresting the valve in an intermediate position so selected that the ram descends during the drawing operation, at a predetermined retarded speed without any attention on the part of the operator.

The invention also contemplates an arrangement of the above character which is simple and economical in construction and may be applied with facility upon the molding machine.

With the above as well as other objects in view, the invention resides in the novel features of construction, combinations and arrangements of parts as will be more fully hereinafter referred to.

In the drawings:

Figure 1 is an elevational view of a molding machine with my invention applied thereto; and

Figure 2 is a fragmentary view partly in elevation and partly in section of the valve controlled arresting means.

Referring now particularly to the drawings wherein like reference characters designate like parts, it will be noted that the molding machine includes a base 10 and a pair of swinging side frame members 11 pivotally connected as at 12 to the base 10. A ram 13 reciprocates in a housing 14 by power, such as air pressure, controlled by a suitable valve 15 to be more fully hereinafter referred to.

The ram 13 carries a plate 16 upon which the flask 17 of the mold is adapted to rest. The reference character 18 indicates generally the pattern plate and 19 the squeezer plate which is carried by the frame 20 of the molding machine. This latter frame member is supported upon the side frame member 11.

As shown in Figure 1, the parts of the molding machine are in a position wherein the pattern is drawn from the mold. In this

connection it will be noted that the pattern plate 18 is held stationary during the drawing operation by means of a pair of mold part engaging elements or clamps 21. The latter being preferably U-shaped in cross section with the upper ends thereof pivotally and adjustably secured to a cross head 22.

The mounting of the clamping elements 21 permit the same to be rocked or swung about a horizontal axis so that the lower looped ends of these clamps may be engaged under the extensions 18' on the plate 18. The clamps are normally urged into operative or engaging position as for instance by means of a spring 21' connected at its ends to brackets 23 secured to one leg of each of the U-shaped clamps. The brackets 23 are provided with downwardly extending portions 24 adapted to engage the adjacent face of the frame member 20 and have a camming action therewith in the following manner: When the handle 24' illustrated in Figure 1 is operated to rotate the cam member 25 to permit the cross head 22 to descend under the action of a spring 26, the downwardly extending portions 24 of the brackets 23 bear upon the upper face of the adjacent frame member at an angle slightly inclined to the vertical, so that as the cross head, and consequently the clamping members, are forcibly urged towards the frame members 20, the engagement of the legs 24 will forcibly swing the clamping members about their pivots and in an outward direction so as to release the pattern plate 18. Obviously when the handle 24' is subsequently rotated to raise the cross head, the arms 24 will be raised clear of the frame members 20 and the relatively weak springs 21' will then function to swing the clamping members into a substantially vertical position wherein they engage under the extensions 18' of the pattern plate.

When the parts are in the foregoing position, the ram 13 may be lowered to withdraw the pattern from the mold. In order to efficiently accomplish this result, the valve 15 is provided for controlling the power for operating the ram 13. The valve is provided with an operating handle 27 pivoted at one end thereof to a projection 28 on the

valve casing and intermediate the ends to a plunger 29 slidably mounted within the valve casing and having a longitudinally extending chamber 30 therein. The plunger preferably terminates at the lower end thereof in an annular valve seat 31 adapted to engage the upper end of a valve member 32 for controlling the exhaust of fluid from the cylinder through the opening 32' formed in the valve 10 casing. The arrangement is such that upon upward movement of the handle and plunger to open the exhaust valve, fluid will flow from the cylinder through the chamber 30 and escape through the opening 32' formed in the 15 upper portion of the chamber. The valve member 32 is also slidably mounted within the valve casing substantially below and in alignment with the plunger 29 and is provided with an enlarged head portion at the 20 lower end thereof adapted to engage a suitable seat 33 formed in the casing to control the entrance of fluid into the cylinder. The member 32 is further provided with a depressed portion 34 operable upon disengaging the head portion aforesaid from the seat 33, to establish communication between the inlet opening 35 and the cylinder. A suitable coil spring 36 normally tends to urge the head of the member 32 into engagement with the 25 seat 33 and thereby maintain the intake passage closed. The exhaust valve on the other hand, is normally urged toward its open position by a second spring 37 adapted to act upon the plunger 29. The operation of the valve is 30 as follows: Assuming that the exhaust valve is in its open position and the intake valve is closed and it is desirable to respectively close and open these valves the plunger 29 is caused to move downwardly against the 35 action of the spring 37 into engagement with the upper end of the valve member 32 thereby closing the exhaust opening. Thus upon further downward movement of the plunger 29 the valve member 32 will also be moved 40 downwardly with the result that the head portion of the member 32 will be disengaged from the valve seat 33, thus permitting the fluid to flow from the source of supply into the cylinder to raise the ram. When it is de- 45 sired to effect a lowering of the ram, the plunger 29 is permitted to move upwardly under the action of the spring 37 thus opening the exhaust valve and permitting the fluid to flow out of said cylinder. It will be noted 50 that at the same time the plunger is moved upwardly by the spring 37, the valve member 32 is also moved upwardly by means of the spring 36, to close the inlet passage. 55 Owing to the fact that when the exhaust 60 valve is open, the ram is descended to withdraw the pattern from the mold, it is desirable to control the extent of opening of this valve so as to permit the air, if compressed air is used, to escape slowly and 65 thereby effect a comparatively slow descen-

sion of the ram. In order to accomplish this result I provide preferably on one of the frame members 11, a lug or stop 38 with which an extension or stop 39 on the handle 27 is adapted to engage. The stop 39 preferably comprises a member secured at one end to the handle 27 adjacent the valve 15 and terminating at the opposite end adjacent the gripping portion of the handle 27. This stop is adjustable by means, for instance, of a bolt 40 projecting upwardly from the handle 27 and adapted to pass through an aperture in the extension 39 and adjustably secured thereto by means of a pair of lock nuts 41. If it is understood that the handle 27 is swung in an upward direction to open the exhaust valve controlling the escape of fluid from under the ram 13, it will be seen that the engagement of the adjustable stop 39 with the stop 38 will locate the handle 27 and consequently position the valve where it is open only to a limited extent. This has heretofore been accomplished manually with the result that the operator had to determine the particular desired position of the handle 27 so that the ram would descend at the desired speed. This latter arrangement has been found objectionable as it frequently happened that the operator neglected to hold the valve in an intermediate position and accordingly the ram, upon reaching the end of its stroke, imparted a sudden shock to the flask and often times cracked the mold. With the present invention however, the valve will be accurately located in the desired position without any special attention on the part of the operator and the extent to which the valve is held open may be governed by regulating the position of the adjustable stop 39. 95

As will be noted from Figure 1 of the drawing, the stop 38 is positioned upon one of the swinging frame members 11 so that after the pattern has been withdrawn from the mold and the frame members 11 swung to inoperative position, the stop 38 will accordingly be moved out of engagement with the adjustable stop 39 permitting the handle 27 to move to a position wherein the exhaust valve is completely open. 105

The operation of the herein described construction will no doubt be readily apparent without further detailed description of the same. One of the embodiments of the invention has been described and illustrated herein in detail but it will be immediately apparent to those skilled in this art that various changes in many of the essential and all of the non-essential details of the invention may be resorted to without departing from the spirit and scope thereof, and to this end reservation is made to make such changes as may come within the purview of the accompanying claims. 115

What I claim as my invention is:

1. In a molding machine, a member mov- 120

130

able to withdraw a pattern from a mold, means for controlling the operation of said member, and means associated with the means aforesaid for controlling the latter to effect a gradual and relatively slow movement of said member during the drawing operation.

2. In a molding machine, a reciprocable ram movable in one direction to withdraw a pattern from a mold, a valve for controlling the operation of said ram, and automatically operable means for controlling the valve to effect a gradual and relatively slow movement of the ram during the drawing operation.

15 3. In a molding machine, a reciprocable ram and valve controlled power means for actuating the ram, and means automatically operable to arrest the valve in an intermediate position for effecting a gradual and relatively slow movement of the ram in one direction.

25 4. In a molding machine, a reciprocable ram and valve controlled power means for actuating the ram, and adjustable means for arresting the valve in a predetermined intermediate position for effecting a relatively slow movement of the ram in one direction.

30 5. In a molding machine including a reciprocal ram and valve controlled power means for actuating said ram, a handle for controlling said valve and an adjustable stop on said handle for arresting the latter in an intermediate position of the valve.

35 6. In a molding machine, a power actuated ram, a handle controlled valve therefor, a stop on the frame of the machine and an adjustable cooperating stop on said handle engageable with said first stop to arrest the handle in an intermediate position of the 40 valve to permit said ram to slowly descend.

45 7. In a molding machine, a power actuated ram, a handle controlled valve therefor, a stop upon the frame of the machine and a second stop upon the handle, one of said stops being adjustable and adapted to engage the other to arrest the handle in a predetermined intermediate position of the valve to permit a relatively slow movement of the ram in one direction.

50 8. In a molding machine, a power actuated ram movable in one direction to withdraw a pattern from a mold, a handle controlled valve therefor, a stop associated with the machine, a second stop upon said handle engageable with the first mentioned stop to arrest the handle in an intermediate position of the valve to permit a relatively slow movement of the ram during the drawing operation, and means permitting said first mentioned stop to 55 be moved out of engagement with said second stop and thereby permit movement of the valve to one extreme position.

60 9. In a molding machine, a reciprocal ram, fluid pressure means for raising said ram, a 65 valve for controlling said fluid pressure

means, means for automatically moving said valve to fluid releasing position, and means for limiting movement of the valve toward the fluid releasing position whereby to effect a gradual and relatively slow descent of the ram.

In testimony whereof I affix my signature.
WILLIAM J. FIEGEL.
